VALVE CONTROLLED MUFFLER WITH A PLURALITY OF THROUGH PASSAGES

Perry B. Fina, New York, N. Y.

Application May 10, 1950, Serial No. 161,169

3 Claims. (Cl. 181—45)

1

This invention relates to muffler structures for connection with internal combustion engines of automotive vehicles.

It is an object of the present invention to provide means affording a very practical and economical muffler construction which is valve-operated so as to either effect direct exhaust of the gases or to lead such gases through muffling material in a silencing chamber.

It is another object of the invention to provide means ensuring ready and easy installation and accommodation of the muffler structure under a car and like vehicle without affecting the required ground clearance of the chassis of the car.

It is a further object of the invention to provide means conducive to an efficient and improved muffler structure, which can be used in racing, as well as touring cars and which combines the advantages of a straight exhaust pipe with those of silencing tubes or chambers.

It is still another object of the invention to provide means facilitating the assembly of the muffler upon the exhaust pipe of the engine and operation of the muffler valve from the dash board of the vehicle, a self-contained muffler unit being achieved, which has a central valve-controlled direct exhaust portion and tubular silencing portions supported by and in communication with said central portion.

It is another object of the present invention to provide a muffler unit having a central pipe portion and diametrically opposing muffler or silencing chamber portions supported by the central pipe portion and in communication therewith whereby to provide for a somewhat flat muffler that requires less head space beneath the vehicle than that required by the large round present day types of muffler.

Other objects of the present invention are to provide a muffler construction of the above type which is simple, inexpensive to manufacture, easy to install upon an exhaust pipe, compact, requires little head space, lends itself to being welded from standard stock pieces, is rugged and efficient in operation.

For other objects and for a better understanding of the invention, reference may be had to the following detailed description taken in connection with the accompanying drawing, in which

Fig. 1 is a top plan view of the muffler embodying the features of the present invention.

Fig. 2 is a longitudinal sectional view of the muffler, the control valve being in the outer end thereof.

Fig. 3 is a longitudinal sectional view of a mod-

ified form of the muffler wherein the control valve is adjacent the inner end of the muffler.

Referring now to the drawings, 10 represents a central muffler or pipe portion having an inlet end 11 and an outlet end 13. The inlet end of the central portion may be connected to an exhaust pipe 14. This inlet end is preferably split so that the connection with the exhaust pipe 14 can be effected through a split clamp 15 which is tightened by bolt means 16 to draw the split portion of the inlet end of the central pipe 10 tightly about the exhaust pipe 14.

Extending laterally from the opposite sides of the central pipe portion 10 are silencing chamber portions 17 and 18. The portion 17 is connected to the side of the pipe 10 by two longitudinally spaced fittings 19 and 20 and the union made by welding is indicated at 21. The silencing chamber portion 18 is similarly connected to the opposite side of the central pipe 10 by fittings 22 and 23 longitudinally spaced from one another.

In the outer end of the central pipe portion 10 is a butterfly valve 24 which has an operating arm 25 and a spring 26 anchored to the pipe portion 25 at 27 to bias the valve to a normally closed position. Connected to the arm 25 is a Bowden flexible cable arrangement 28 for operating the butterfly valve 24. This arrangement includes a wire 29, a flexible casing 31 and a mounting bracket 32 for securing the cable assembly to the muffler or silencing chamber portion 18. When the butterfly valve 24 is turned to a closed position, the exhaust gases will be diverted to the silencing chamber portions 17, 13 and will enter such portions from the central portion through the fittings that connect the portions 17 and 18 with the central portion 10. The silencing chamber portions 17 and 18 are respectively provided with closed front ends, as indicated at 34 and 35 respectively, whereas the rear ends are perforated and open, as indicated at 36 and 37, respectively, so that the muffled gases may be discharged from the rear ends 36, 37 of these portions. While some of the gases will pass through the fittings 19 and 22, the larger bulk of the gases will pass through the rear fittings 20 and 23. The chamber portions are provided with the usual wool or silencing material 38, such as brass wool, etc.

According to the form of the invention shown in Fig. 3, the valve element is located near the inlet end of the central pipe portion and between the spaced fittings of the silencing chamber portions. Accordingly, when the valve in Fig. 3 is closed, all of the gases must pass through the inner fittings 19 and 22 and may discharge

through the outer ends of the portions 17 and 18 and to some extent through the fittings 20 and 23 and the outlet end of the central pipe portion 10. Maximum silencing material lying between the fittings of the respective silencing chamber portions is thus put into play, the distances between the fittings of the respective silencing chamber portions being greater than between the outlet end fittings at the perforated ends of the respective silencing chamber portions.

It will be apparent that there has been provided a muffler which can be made of standard stock or pipe pieces wherein the silencing chamber portions extend diametrically opposite to one another from a central portion of the same stock material and wherein the muffler is generally of flat construction whereby to consume little head space under a vehicle. The butterfly valve is an integral part of the pipe assembly and can be connected therewithin at any location within the central pipe 10 depending upon the use to which the muffler is to be put.

It is further to be noted, that the diameters of the pipe connections or fittings 20, 23 may differ (being larger or smaller) from those of the fittings 19, 22; in some cases it may be considered advantageous to omit these interconnecting fittings 20, 23. In such latter event, it is proposed to direct silencing tube portions 17, 18 in such manner that they converge toward the outlet end 13 of the exhaust tube 10.

Although the construction as shown, may be achieved from stock tube material, it is well apparent that the valve-controlled central and unobstructed muffler portion may be formed by partitions placed in a hollow body which is otherwise filled with silencing material, the communication between said central portion and the lateral silencing portion being effectuated without fittings and ahead of the valve accommodated in said central portion.

While various changes may be made in the detail construction, it shall be understood that such changes shall be within the spirit and scope of the present invention as defined by the appended claims.

Having thus described the invention, what is claimed as new and desired to be secured by Letters Patent, is:

1. A muffler construction comprising a central pipe portion having an inlet and outlet end, said inlet end being adapted to be secured to an exhaust pipe of an internal combustion engine, silencing chamber portions each provided with front end and rear end and disposed at opposite sides of the central pipe portion interconnecting fittings longitudinally spaced from one another and establishing communication of the respective silencing chamber portions with the central pipe portion intermediate said inlet and said outlet end thereof, silencing material accommo-

dated in said silencing chamber portions, said front ends of the silencing chamber portions being closed while the rear ends are open, and valve means arranged forwardly of said fittings in said central pipe portion and operable to either permit the passage of said exhaust gases through the central pipe portion or to divert same through said fittings and the rear ends of the silencing chamber portions.

10 2. A muffler construction comprising an open central pipe portion having an open inlet end and an open outlet end, said inlet end being adapted to be connected to an exhaust pipe of an internal combustion engine, multiple silencing chamber portions each provided with a front end and with a rear end, said silencing chamber portions being provided with longitudinally spaced fittings disposed, respectively, adjacent the inlet end and the outlet end of the open pipe portion and establishing communication between the latter and said silencing chamber portions, said silencing chamber portions being closed at their front ends and being perforated at said rear ends, said silencing chamber portions being positioned independently of each other and in side by side relation to said open central pipe portion and being supported thereon by said fittings, and valve means in said central pipe portion and disposed adjacent fittings which are arranged at one of said ends of said open central pipe portion, and said valve means being operable to either permit the free flow of gases through said open pipe portion or to divert said gases from said inlet end through said fittings of said silencing chamber portions toward said perforated rear ends thereof, the diameter of said central pipe portion being substantially similar to that of said silencing chamber portions.

3. A muffler construction according to claim 2, wherein said silencing chamber portions are filled with known silencing material.
